Primary Examiner — Aula Soroush(74) *Attorney, Agent, or Firm* — Artegis Law Group, LLP(57) **CLAIM**

The ornamental design for a nasal interface for ventilation, as shown and described.

DESCRIPTION

FIG. 1 is a top perspective view of a nasal interface for ventilation, showing our new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof;

FIG. 7 is an enlarged top perspective view thereof;

FIG. 8 is a left side view thereof as would be positioned in a nostril, the right side being a mirror image; and

FIG. 9 is an enlarged top perspective view thereof; and, FIG. 10 is an enlarged cross-sectional view taken in the direction of lines 10-10 of FIG. 9.

The broken lines in the figures form no part of the claimed design.

1 Claim, 10 Drawing Sheets(56)
